JOSEPH MESSMER, OF KIRKWOOD, MISSOURI, ASSIGNEE TO CONTINENTAL BRASS & FOUNDRIES COMPANY, OF ST. LOUIS, MISSOURI, A CORPORATION OF MISSOURI.

THERMOSTATIC VALVE.

1,273,899.

Specification of Letters Patent.

Patented July 30, 1918.

Application filed September 26, 1917. Serial No. 193,268.

To all whom it may concern:

Be it known that I, JOSEPH MESSMER, a citizen of the United States of America, residing in the city of Kirkwood, county of 5 St. Louis, State of Missouri, have invented certain new and useful Improvements in Thermostatic Valves, of which the following is a specification.

This invention relates primarily to valves 10 designed to effect improvement in the operation of that modern method of heating which has come to be known as the "vapor vacuum" system, wherein all water of condensation and air collecting in the radiators 15 is conveyed to pipes located in the basement of the building and carried past a thermostatic valve adapted to permit the escape of air while insuring the return of said water to the boiler; the object of this invention being to afford a valve of the character specified embracing novel means which, while permitting the escape of air, will prevent its suction into the system and close against the escape of steam or water carried by said 25 pipes which shall hereinafter be referred to as the air exhaust line.

Referring to the accompanying drawing, wherein like numerals refer to like parts throughout the several views, Figure 1 is 30 an isometric view depicting the typical manner of connecting a radiator to the furnace in the particular system of heating here involved; Fig. 2 a sectional elevation of the thermostatic valve; Fig. 3 a cross-section 35 of the valve taken along line 3—3 of Fig. 2; Fig. 4 a cross-section taken along line 4—4 of Fig. 2; Fig. 5 a cross-section taken along line 5—5 of Fig. 2; and Fig. 6 a cross-section taken along line 6—6 of Fig. 2.

40 By reference to Fig. 1 it will be appreciated that steam generated within boiler 1 is conveyed by pipes 2 and 3 into the main circulating pipes 4 and carried thence to radiator 5 by riser 6 which is surmounted with a control valve 7. The base of each 45 radiator is connected by pipe 8 with the air exhaust line 9 and it will be noted that the valve of my invention is interposed at a point adjacent to the vertically disposed section 9^a of said line which connects with the boiler. Said valve comprises a pipe 10 threaded at 11 for insertion in the air exhaust line and serving as the housing for a hollow cylindrical float 12 whose lower end 55 is closed by a removable threaded cap 14.

Said float is retained in vertical position by ribs 15 cast upon the inner surface of said pipe, its downward movement being limited by shoulder 16 while upon being raised its rounded upper extremity engages the concave seat 17 provided in plate 18 and thus closes port 19 above which is disposed a baffle-plate 20. The upper end of pipe 10 is cast integral with a cylindrical shell 21 to which is coupled a plug 22 provided with a threaded bore 23 closed by a removable cap 24, said bore serving to support the threaded extremity of the valve-stem 25 which is slotted at 26 to permit adjustment by aid of a screw-driver.

Secured upon the opposite extremity of stem 25 is a thin metal disk 27 to which is soldered the flange 28 of a companion disk 29, the latter being affixed to a short rod 30 and the annular compartment 31 thus 70 formed being filled with a readily vaporizable liquid so as to effect distention of disk 29, with consequent forward movement of said rod, coincident with the passage of steam into chamber 32. Rod 30 is connected by set-screw 33 with the plunger 33^a which is capped with a disk 34 of rubber or other suitable material and projects within sleeve 35, it being observed that the latter is provided with ribs 36 for the support of 80 the plunger and that, as shown in Fig. 3, spaces 37 are provided between said sleeve and plunger for the escape of air. Disk 34 is disposed in close proximity to port 38 and being slightly larger than said port is adapted to close the same upon being moved forward, with plunger 33 and rod 30, upon expansion of the fluid contained in compartment 31, while the vacuum created upon retraction of said plunger serves, in conjunction with atmospheric pressure, to retain the hingedly supported disk 39 closely against the external rim of said port and thus prevents the admission of air.

Having thus fully described the structure 100 of the valve, we may now proceed to its operation and for present purposes shall assume that the furnace has been checked for a period sufficient to allow the radiators and supply pipes to cool. The drafts being 105 opened and the boiler heated, the steam generated is conveyed by pipes 2, 3, 4 and riser 6 to the radiators and condensed to a degree while filling the same. The water resulting from this condensation, together with the 110

air which has accumulated in the supply pipes and radiators, is eventually forced from the latter into pipe 8 and thence carried to the valve above described by the return line 9. Upon reaching this point the air (obviously preceding the water) seeks the path of least resistance and passing upward through the space provided between member 12 and the inner surface of pipe 10 escapes through port 38. The water coming next and with considerable force lifts member 12 against seat 17 and thus closes port 19, but as the flow thereof is, at the outset, intermittent it follows that member 12 may momentarily descend sufficiently to permit the passage through said port of spouts or jets carrying sediment collected from the radiators and this solid matter might accumulate to such an extent as to obstruct the closing of port 38 were it not for the provision of baffle-plate 20 which checks the escaping water and deflects the sediment backward through port 19. The water being finally forced downward through section 9^a of the return line into the boiler by pressure of the steam which follows its travel through said line, member 12 is released from its seat and the steam then passing into the upper portion of the valve effects expansion of the fluid within compartment 31 with the result that port 38 is automatically closed.

Having thus described the invention, what I claim as new and desire to secure by Letters-Patent is:—

1. A valve for heating systems, comprising a tube connected with the air-exhaust line of the system having a port for the escape of air, a plunger disposed within said tube opposite said port, a thermally sensitive element mounted upon the stem of said

plunger, a member adapted to prevent the admission of air through said port, and a baffle-plate disposed between said line and tube. 45

2. A valve for heating systems, comprising a tube connected with the air-exhaust line of the system having a port for the escape of air, a plunger disposed within said tube opposite said port, a thermally sensitive element mounted upon the stem of said plunger, a member positioned exteriorly of said tube adapted to prevent the admission of air through said port, and a baffle-plate disposed between said line and tube. 50 55

3. A valve for heating systems, comprising a tube connected with the air-exhaust line of the system having a port for the escape of air, a plunger disposed within said tube opposite said port, a thermally sensitive element mounted upon the stem of said plunger, a member adapted to prevent the admission of air through said port, a baffle-plate disposed between said line and tube, and means for preventing the passage of water from said line into said tube. 60 65

4. A valve for heating systems, comprising a pipe projecting from the air-exhaust line of the system, a tube connected with said pipe having a port for the escape of air, a restricted opening between said tube and pipe, a baffle-plate disposed above said opening, a float within said pipe adapted to close said opening, a plunger disposed within said tube opposite said port, a thermally sensitive element mounted upon the stem of said plunger, and a member adapted to prevent the admission of air through said port. 70 75

JOSEPH MESSMER.
